NECKTIE RACK

George L. Pilliod and Alfred O. Judson, Swanton,
Ohio, assignors to The Pilliod Cabinet Company,
Swanton, Ohio, a corporation of Ohio

Application June 23, 1938, Serial No. 215,367

7 Claims. (Cl. 211—89)

This invention relates to article display or holding racks, and particularly to such a rack adapted particularly to hold neckties, but may be used for other articles.

5 The primary object of the invention is the provision of a simple, efficient and inexpensive article holding rack of the character described, which has a pair of laterally opposed parallel bar members held in yielding coacting relation to grip 10 one or more neckties, or similar articles, therebetween, the bar members being adapted to have the articles inserted therebetween from either end thereof.

15 Further objects and advantages of the invention will be apparent from the following detailed description, and from the accompanying drawing illustrating the same, in which—

20 Figure 1 is a perspective view, in set-up usable position, of a rack embodying the invention; Fig. 2 is a top edge view thereof, with its collapsed position shown in dotted lines; Fig. 3 is a section on the line 3—3 in Fig. 2; Fig. 4 is a rear elevation of one end portion thereof, and Fig. 5 is a rear perspective view of one end portion of the 25 rack showing a different manner of attaching the spring wire members to the body member.

25 Referring to the drawing, and particularly to Figs. 1 to 4, 10 is a back plate or board adapted to be placed against and attached to a wall, or 30 other suitable support, by screws 11 and being narrow in vertical dimension and of a considerable length horizontally. It is found that eighteen to twenty inches is a desirable length for a necktie rack.

35 The back member 10 is equipped with two U-shaped bar holders 12, which straddle said member with their loop or cross portions 12^a disposed crosswise of the member at the rear thereof and held seated freely in respective cross-sections 13 by staples 14. The holders 12 are made of 40 spring wire, and their legs 12^b extend forward from the back member 10 and have their free ends turned inward to form axially opposed pintles 12^c for fitting into sockets 15 in the outer 45 side edges of a pair of opposed parallel article gripping bars 16.

The bars 16 are of thin slat form, preferably longer in length than the back member 10, with their inner edges yieldingly coacting and adapted 50 to grip neckties 17, or other articles, therebetween. The adjacent edges of the bars are beveled at their ends to provide tapering entrance spaces 18 to facilitate insertion of articles between the bars.

The spring holders 12 may be held at right 55 angles, or in forwardly projecting relation to

the back member 10 by the upper legs thereof seating in respective recesses 19 in the top edge of said member, or the holders may be raised to remove the legs thereof from said recesses, thus permitting the holders and bars to be swung into collapsed or folded relation to the body member, as shown by dotted lines in Fig. 2.

In the form shown in Fig. 5, the spring holder members, which are designated 20 therein, have the loop portions thereof provided with transversely extending loop or tongue portions 21 disposed at right angles to the plane of projection of the legs of the holder and adapted to seat in respective recesses 22 provided in the rear side of the back board or member 23. The loops 21 are secured flat within such recesses by the coaction of the member with a wall or other support when secured thereto. This manner of attaching the holder springs to the back member causes them to be held in set-up relation to such member when the member is in position against a wall and enables them to be knocked down or collapsed with respect to the back member when such member is removed from a wall, as is apparent.

It is apparent that we have provided a simple, 25 inexpensive and attractive form of article holding rack of a type particularly adapted for the holding of neckties; that the bars 16 are yieldingly held in gripping relation by the spring holder 12 or 20, as the case may be, and that 30 said bars, when separated, provide a prolonged space therebetween, in which a plurality of neckties or similar articles may be inserted and yieldingly held by the spring pressed gripping action of the bars. It is also apparent that the adjacent 35 edges of the bars are smooth and parallel so that articles may be forcefully moved lengthwise of the bars when the bars are in gripping engagement therewith.

We wish it understood that our invention is 40 not limited to any specific construction, arrangement or form of the parts, as it is capable of numerous modifications and changes without departing from the spirit of the claims.

Having thus described our invention, what we 45 claim as new, and desire to secure by United States Letters Patent, is:

1. In a rack of the class described, a back member, a pair of laterally opposed upper and 50 lower article gripping bars, one or more U-shaped members carried by said back member with their legs projecting forward therefrom in vertically spaced relation, and engaging and carrying at their outer ends the respective upper and lower 55

bars and normally retaining the bars in article gripping relation.

- 5 2. In a rack of the class described, a back member, two or more U-shaped springs carried by the back member with their looped portions at the rear side thereof and their legs extending forwardly in vertically spaced relation from the back member, the free ends of said legs being turned toward each other to form substantially axially aligned pintles, and a pair of laterally opposed upper and lower article gripping bars carried respectively by the pintles of said upper and lower legs and held in yielding coacting article gripping relation thereby.
- 10 3. In a rack of the class described, a back member, a U-shaped spring wire straddling the back member with its loop disposed at the rear thereof and its legs projecting forwardly, said back member having a recess for receiving said loop and having provision for coacting with the spring member for preventing it from turning lengthwise of the back member, and a pair of laterally opposed upper and lower substantially parallel article gripping bars yieldingly carried by the respective upper and lower leg portions of the spring wire, each leg being pivotally connected to its bar.
- 15 4. In a rack of the class described, a back member, a plurality of U-shaped spring members straddling the back member with their legs projecting forwardly therefrom, said back member cooperating with the spring members to retain them in forwardly projecting position and permitting swinging collapsing movement thereof relative to the back member, a pair of laterally opposed upper and lower article gripping bars pivotally carried respectively by the upper and lower legs of said spring members and held in yielding article gripping coaction by said legs.
- 20 5. In a rack of the class described, a back member having recesses in its top edge, a U-shaped spring member straddling the back member in association with each of said recesses and adapted to have its legs project forward therefrom.

5 with one leg seating in the respective recess and with the other leg spaced below the back member a distance necessary to permit the spring member to be moved laterally of the back member to withdraw its upper leg from such recess and permit collapsing movement of the spring member relative to the back member, and a pair of laterally opposed upper and lower article gripping bars carried respectively by the upper and lower legs of said spring members, whereby the 10 bars are held in yielding coaction, said bars having their adjacent surfaces beveled at their ends to provide an article entrance recess between the ends of the bars.

15 6. In a rack of the class described, a back member, a plurality of U-shaped spring members straddling the back member with their looped portions extending crosswise of the back member and their legs projecting forwardly therefrom, said loop portions being themselves looped laterally at substantially a right angle to the leg portions to lie flat against the back side of the back member, securing means engaging said laterally looped portions and the back member, and a pair of laterally opposed parallel upper and lower article gripping bars carried respectively by the upper and lower legs of said spring members and held in yielding article coacting relation by said spring members.

20 7. In a rack of the class described, a back member, a pair of article gripping bars in advance of said member, a plurality of spring members carried by said back member and having arms projecting forward therefrom and in pivotal supporting engagement with respective of said bars 35 to normally retain them in coacting clamping engagement and permitting yielding lateral movements and longitudinal collapsing movements thereof relative to the back member, said spring members being collapsibly connected to the back 40 member.

CERTIFICATE OF CORRECTION.

Patent No. 2,167,994.

August 1, 1939.

GEORGE L. PILLIOD, ET AL.

It is hereby certified that error appears in the printed specification of the above numbered patent requiring correction as follows: Page 1, second column, line 51, claim 1, after "U-shaped" insert the word spring; and that the said Letters Patent should be read with this correction therein that the same may conform to the record of the case in the Patent Office.

Signed and sealed this 12th day of September, A. D. 1939.
